UNITED STATES PATENT OFFICE.

REUBEN N. TRANE, OF LA CROSSE, WISCONSIN.

CENTRIFUGAL PUMP.

1,418,041.

Specification of Letters Patent. Patented May 30, 1922.

Application filed November 11, 1920. Serial No. 423,428.

To all whom it may concern:

Be it known that I, REUBEN N. TRANE, a citizen of the United States, and a resident of La Crosse, in the county of La Crosse and 5 State of Wisconsin, have invented a new and useful Improvement in Centrifugal Pumps, of which the following is a full, clear, and exact description.

My invention relates to pumps of the centrifugal type, and it consists in the combinations, constructions, and arrangements herein described and claimed.

An object of my invention is to provide a pump in which the friction is reduced 10 to a minimum, and at the same time to provide a construction with which it is possible to pump higher pressures than can ordinarily be attained with a single stage centrifugal pump.

20 A further object of my invention is to provide a construction in which the number of stages may be increased, whereby higher heads may be built up than is possible with a single stage.

25 A further object of my invention is to provide a device in which the pumping characteristic may be readily changed, so as to increase the quantity of water or other fluid being pumped, or to increase or decrease the 30 limiting pressure by changing the ratio of the area of the blades of the impeller and the number of blades, to the area of the channel through which the water flows.

35 A further object of my invention is to provide a construction which can be readily made, because the parts are circular and can be machined to a great degree of accuracy, thereby preventing leakage.

40 Other objects and advantages will appear in the following specification, and the novel features of the invention will be particularly pointed out in the appended claims.

45 My invention is illustrated in the accompanying drawings, forming part of this application, in which—

Figure 1 is an end elevation of one form of the device.

50 Figure 2 is a vertical section along the line 2—2 of Figure 1,

55 Figure 3 is a section along the line 3—3 of Figure 1,

Figure 4 is a fragmentary perspective view of a portion of the impeller.

60 Figure 5 is a section along the line 5—5 of Figure 1,

Figure 6 is a view of a portion of a modified form of the device,

Figure 7 is an end view of a double stage pump, the cover plate being removed, and

Figure 8 is a section along the line 8—8 60 of Figure 7.

In carrying out my invention, I provide a suitable base 1 having bearings 2 for a shaft 3. The latter passes through a stuffing box 4, which also serves as a bearing. In the present instance I have shown a casing having a portion 6 integral with the base 1. It is obvious that the casing may be a separate member and secured to the base. Carried by the casing is a cover plate 7 which is secured to the casing by bolts 8, or in any other suitable manner. The cover plate in this instance has a centrally disposed inlet 9, while at the top of the casing (shown in Figure 2) is an outlet 10. The interior of 70 the casing is hollowed out in cylindrical form to provide a chamber 11.

Mounted on the shaft 3 is the impeller. This consists of a hub 12, spokes or a web 13, and a rim 14. The latter is provided 80 with an annular groove 15. A portion of this groove is taken up by impeller blades 16 of the shape best shown in Figure 4. The groove 15 forms a channel through which the water flows, as will be explained later. It 85 will be noted that the blades 16 extend inwardly from the side walls of the groove 15, but there is a space between the ends of the inwardly extending opposed blades. In Figure 4 I have shown these blades as having 90 curved sides. While this is the preferred form, since it is easier to cut the blades with a round tool, a straight blade might be used very effectively. The blades 16 take up only a small portion of the area 95 of the channel, usually in the neighborhood of one-fifth to one-sixth of the area.

Disposed on one side of the outlet is a block 17 which, as will be seen from Figure 5, extends into the annular groove 15. The 100 block is held by a bolt 18 and is designed to prevent the passage of water or other fluid past the point where the block is located, or, in other words, to direct it into the discharge opening.

105 From the foregoing description of the various parts of the device, the operation thereof may be readily understood. The device is driven through any suitable means, as by a belt (not shown) applied to the 110

pulley 19. As the impeller revolves, the water or other fluid is drawn in through the inlet 9, and passes through that portion of the circular channel 11 outside of the wheel 5 to the opening 20. Here it enters the annular groove 15 in the impeller wheel, and a portion is caught by the blades 16 and carried around. That portion between the blades also is moved by the impeller wheel 10 in the direction in which the wheel is rotated, and is carried around until it reaches the abutment block 17, when it is forced out of the discharge opening 10. I desire to call particular attention to the fact that this 15 construction differs from those constructions in which the water or fluid, being pumped, is moved in a channel in the casing. In such instance there is friction on the three sides. In the present instance, however, the 20 water travels with the wheel, and therefore does not meet with the friction which it would meet with if traveling through stationary walls of the casing. This results in a greater efficiency.

25 In Figure 6, I have shown a modified construction, in which the inlet opening, instead of being at the central portion of the casing, is disposed near the outlet. Thus in Figure 6, the outlet 10_a has near it the inlet 9_a, the outlet and the inlet being separated by the abutment block 17. In this instance, the water, entering the inlet 9_a, passes into the annular channel or groove 15 in the impeller wheel, and is carried clear around to 30 the abutment block before leaving the casing.

35 It is sometimes advantageous to have the water acted on in separate stages. To this end I provide the construction shown in Figures 7 and 8. Referring particularly to 40 Figure 8, it will be seen that the casing 1_a is provided with an inlet 21, and an outlet 22. The impeller wheel has two grooves which are shown at 15_a and 15_b respectively, 45 There are two portions of the impeller wheel, one in each groove. There are also two abutments. The water or other liquid enters the inlet 21, and passes into the channel 15_a. Here it is carried around the channel until it meets the abutment block 17_a 50 (see Figure 2). It then passes through the opening 20' into the channel 15_b, and is carried around in the channel 15_b until it meets the abutment block 17_b, whence the water is forced out of the outlet 22.

55 In both forms of the device, that is to say, in the single stage pump, as well as in the multiple stage pump, the water is carried around in the channel of the moving impeller, the friction on three sides thereby being eliminated. Since the power required 60 to drive the pump is largely used in overcoming friction, it will be at once apparent that the reduction of the friction in this manner leads to great economy in the operation of the device, and a high efficiency.

I claim:

1. A pump of the type described, comprising a casing having a cylindrical chamber, an impeller wheel mounted for revolution with said chamber, said impeller wheel having a circumferential groove or channel, and a series of blades carried by said impeller wheel and disposed within said channel, said blades extending at right angles to the plane of revolution of the impeller wheel and terminating short of the outer edges of the groove.

2. A pump of the type described, comprising a casing having a cylindrical chamber, an impeller wheel mounted for revolution with said chamber, said impeller wheel having a circumferential groove or channel, a series of blades carried by said impeller wheel and disposed within said channel, said blades extending at right angles to the plane of revolution of the impeller wheel and terminating short of the outer edges of the groove, an inlet for conveying fluid to said groove, an outlet, and means for deflecting the fluid from the groove through said outlet.

3. A pump of the type described, comprising a casing having a cylindrical chamber, an impeller wheel mounted for revolution with said chamber, said impeller wheel having a circumferential groove or channel, a series of blades carried by said impeller wheel and disposed within said channel, said blades extending at right angles to the plane of revolution of the impeller wheel and terminating short of the outer edges of the groove, an inlet for conveying fluid to said groove, an outlet, and means for deflecting the fluid from the groove through said outlet, said last named means comprising an abutment block secured to said casing and arranged to extend into said groove.

4. A pump of the type described, comprising a casing having a cylindrical chamber, an impeller wheel mounted for revolution with said chamber, said impeller wheel having a circumferential groove or channel, a series of blades carried by said impeller wheel and disposed within said channel, said blades extending at right angles to the plane of revolution of the impeller wheel and terminating short of the outer edges of the groove, an inlet for conveying fluid to said groove, an outlet, and means for deflecting the fluid from the groove through said outlet, said last named means comprising an abutment block secured to said casing and arranged to extend into said groove and between certain of said blades.

5. A pump of the type described, comprising a casing having a cylindrical chamber, an impeller wheel mounted centrally with respect to said casing for revolution therein, said impeller being provided with a circumferential groove, blades carried by said im-

- 5 peller wheel within said groove, said blades projecting inwardly from both side walls of the groove, the edges of the opposed blades being spaced apart, and the outer ends of the blades terminating short of the outer edges of the side walls of the groove, an inlet communicating with the groove and for delivering fluid thereto, an outlet in the casing wall, and a stationary abutment block 10 carried by said casing and arranged to extend into the space between the side walls of the groove, and having a portion adapted to extend between the edges of the opposed blades.
- 15 6. A pump of the type described, comprising a casing having a cylindrical chamber, an impeller wheel mounted for revolution within said casing and having a plurality of circumferential grooves or channels, 20 said casing having a passage-way for establishing communication between said grooves, an inlet communicating with one of said grooves, an outlet communicating with the other groove, a stationary abutment carried 25 by the casing and arranged to extend into one of said grooves for deflecting the fluid from said groove into the companion groove, and having a second abutment carried by the casing and arranged to extend into said 30 last named groove for deflecting the fluid through said outlet.
7. A pump of the type described, comprising a casing having a cylindrical chamber, an impeller wheel mounted for revolution 35 within said casing and having a plurality of circumferential grooves or channels, said casing having a passage-way for establishing communication between said grooves, an inlet communicating with one of 40 said grooves, an outlet communicating with the other groove, a stationary abutment carried by the casing and arranged to extend into one of said grooves for deflecting the fluid from said groove into the companion 45 groove, and having a second abutment carried by the casing and arranged to extend into said last named groove for deflecting the fluid through said outlet, and means carried by said impeller wheels within the 50 grooves for forcing fluid therethrough.
8. A pump of the type described, comprising a casing having a cylindrical chamber, an impeller wheel mounted for revolution within said casing and having a plurality of circumferential grooves or channels, 55
- 5 said casing having a passage-way for establishing communication between said grooves, an inlet communicating with one of said grooves, an outlet communicating with the other groove, a stationary abutment carried by the casing and arranged to extend into one of said grooves for deflecting the fluid from said groove into the companion groove, and having a second abutment carried by the casing and arranged to extend into said last named groove for deflecting the fluid through said outlet, and a plurality of opposed blades extending inwardly from the side walls of each groove for forcing fluid through the grooves.
- 60 9. A device of the type described comprising a cylindrical chamber, an impeller wheel disposed in said casing, said impeller wheel having the same diameter as the inner diameter of said casing and being spaced 65 from the side walls of said casing, said impeller having a circumferential groove, a series of blades carried by said impeller and being disposed within said channel, said blades extending at right angles to the plane 70 of the revolution of the impeller and terminating short of the outer edges of the groove, an inlet and an outlet extending radially from said impeller and being disposed adjacent to one another, and a block carried 75 by said casing and projecting into said groove and being adapted to guide a fluid from said inlet into said groove and from said groove into said outlet.
10. A device of the character described 80 comprising a cylindrical casing, an impeller wheel carried by said casing, the periphery of said impeller rotatably engaging the peripheral wall of said casing, said casing having its side walls spaced from said impeller, 85 said impeller having two circumferential grooves, a series of blades carried by said impeller and being disposed within said channel, said blades extending at right angles to the plane of revolution of the impeller and terminating short of the outer 90 edges of the groove, an inlet communicating with one groove, an outlet communicating with the other groove, blocks carried by said casing and being adapted to connect the 95 grooves with their respective inlet or outlet, and a passage communicating with said grooves, said blocks being adapted to divert a fluid from one groove to the other groove.

REUBEN N. TRANE.
